US00D764811S

(12) **United States Design Patent**
Schuller et al.

(10) **Patent No.:** US D764,811 S
(45) **Date of Patent:** ** Aug. 30, 2016

(54) **SHEET HAVING A PATTERN**

- (71) Applicant: **The Procter & Gamble Company**, Cincinnati, OH (US)
- (72) Inventors: **David William Schuller**, Lebanon, OH (US); **Richard Christopher Hagee**, Cincinnati, OH (US); **Diana Woehnl Juratovac**, Columbus, OH (US)
- (73) Assignee: **The Procter & Gamble Company**, Cincinnati, OH (US)
- (**) Term: **15 Years**
- (21) Appl. No.: **29/529,859**
- (22) Filed: **Jun. 11, 2015**

Related U.S. Application Data

- (62) Division of application No. 29/473,098, filed on Nov. 19, 2013, now Pat. No. Des. 734,618.
